UNITED STATES PATENT OFFICE.

WILLIAM C. GULDE, OF ST. PAUL, MINNESOTA, ASSIGNOR TO LAWRENCE WELP, OF BANCROFT, IOWA.

EYESHIELD.

Application filed May 26, 1924, Serial No. 715,981. Renewed May 12, 1925.

To all whom it may concern:

Be it known that I, WILLIAM C. GULDE, a citizen of the United States, residing at St. Paul, in the county of Ramsey and State of Minnesota, have invented a new and useful Eyeshield, of which the following is a specification.

This invention relates to eye shades, and aims to provide a novel form of eye shade which may be readily and easily applied to an eyeglass frame for supporting the shield.

Another important object of the invention is to provide a shield of this character which may be conveniently folded to facilitate the carrying thereof in the pocket of the user.

A still further object of the invention is to provide a shield which will extend across both eye glass frames to shield the eyes of the user.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is an elevational view showing a shield constructed in accordance with the present invention.

Figure 2 is a plan view thereof.

Figure 3 is a sectional view taken on line 3-3 of Figure 2.

Referring to the drawings in detail, the frame of the eye glass to which the shield is applied is indicated generally by the reference character 5.

The shield includes an elongated body portion 6 formed with a curved outer surface acting as a housing for the shield proper, to be hereinafter more fully described. Secured to the elongated body portion 6 at

points adjacent to the ends thereof, are curved sections 7 which are secured by means of the rivets 8 and extend rearwardly with respect to the eye glass frame on which the shield is positioned.

Clips 9 are also secured to the curved body portion 6 and afford means whereby the body portion may be conveniently positioned over the eye glass frame. Supporting bows 10 are curved to fit within the curved portion of the elongated body portion 6, and as shown, the bows have their ends pivotally connected at 11 to permit the bows to be folded to their inactive positions.

A flexible covering 12 is supported by the bows 10 and is adapted to fold within the curved portion of the elongated body 6 when the shield is moved to its inactive position.

Secured to the sections 7 are curved bows 13 which have their ends pivotally connected at 14, and as shown these bows support flexible members 15 which may also be folded within the curved portions of the sections 7 when it is desired to move the shields to their inactive positions.

I claim:

An eye shade including a curved body portion, means for securing the curved body portion to the frame of an eye glass, said body portion having a concaved outer surface, curved members secured to the inner surface of the body portion adjacent to the ends thereof, said curved members having concaved inner surfaces, a flexible covering supported by the body portion and adapted to move within the outer concaved surface thereof, flexible members at the ends of the body portion and adapted to move within the concaved surfaces of the curved members that are secured to the inner surface of the body portion.

In testimony that I claim the foregoing as my own, I have hereto affixed my signature.

WILLIAM C. GULDE.
